UNITED STATES PATENT OFFICE.

AMANDA OBERG, OF HAGER CITY, WISCONSIN.

BOTTLE-STOPPER.

1,278,370.

Specification of Letters Patent. Patented Sept. 10, 1918.

Application filed February 23, 1917. Serial No. 150,550.

To all whom it may concern:

Be it known that I, AMANDA OBERG, a citizen of the United States, residing at Hager City, in the county of Pierce and State of Wisconsin, have invented certain new and useful Improvements in Bottle-Stoppers, of which the following is a specification.

This invention relates to bottle stoppers and more particularly to a device of this character associated with milk bottle caps for providing a conveniently removable cap and stopper for a milk bottle to thoroughly protect the contents of the same.

One of the objects of the invention is to provide a device of this character that may be attached to or detached from a milk bottle thus permitting the device to be interchanged when the contents of one bottle has been used.

Another object of the invention is to provide a hingedly mounted closure for the top of a milk bottle and adapted to have detachably fixed thereto a stopper of cork or fibrous material similar to the common expedient of a fibrous disk now generally employed in milk bottles, whereby the same may be detached and a new stopper attached to the closure when continued use renders the original stopper unfit for further service.

The invention further aims to provide a device of this character that will include a latch for tightly holding the closure in engagement with the top of the bottle neck thus excluding the possibility of foreign matter gaining access to the interior of the bottle.

A further object of this invention is the provision of a bottle stopper which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a side elevation of a portion of a milk bottle showing the invention applied.

Fig. 2 is a top plan.

Fig. 3 is a section on the line 3-3 of Fig. 2.

Fig. 4 is an edge elevation of the device detached from the bottle.

Fig. 5 is a section on the line 5-5 of Fig. 4.

Fig. 6 is a section on the line 6-6 of Fig. 4.

Referring to the drawing, wherein is illustrated the preferred form of my invention, and in which like numerals of reference indicate corresponding parts throughout the several views, the bottle A is provided at the top of the neck with the usual annular bead B which forms the flange for the neck of the bottle. The top of the neck is provided with the annular recess C, in the usual manner, thereby forming a ledge D for receiving a suitable stopper which is usually in the form of a disk of fibrous material.

Extending around the neck of the bottle and beneath the bead B is a retaining band 1 in the form of a metallic ring constructed of a flat strip of suitable material. Integrally formed with the upper edge of the ring or band 1 and intermediate the ends thereof is a tongue 2 that is curved to fit around the bead B and the terminal of this tongue is rolled to provide an eye for forming a part of a hinge 3. This hinge is provided with a pintle which receives the eye of the hinge carried by the closure cap 4 in the form of a circular disk adapted to fit over and rest upon the top of the bottle neck. Diametrically opposite to the hinge eye formed on the closure cap 4 is a latch 5 which consists of an extension bent to fit over the bead B and to be depended to contact with the ends of the band 1. These ends 6 are brought together as clearly shown by Fig. 5 of the drawing and are passed through the slot 7 formed in the terminal of the latch 5. This construction tightly holds the closure disk 4 in engagement with the top of the bottle and prevents accidental displacement thereof.

A suitable cork stopper 8 is mounted in the annular recess C and rests upon the ledge D. This stopper is fixed to the closure disk through the medium of a clip 9 which consists of a strip of suitable thin metallic material extended through slits formed in the stopper and also through slots 10 formed in the closure disk 4 whereupon the ends of the strips are bent to lie in engagement with the top surface of the closure disk thereby fixing the stopper to the disk and movable therewith when the disk is raised or lowered.

In this connection, it is pointed out, that the stopper 8 may be in the form of the ordinary fibrous disk now generally employed for the tops of milk bottles since, it is obvious, that should the stopper 8 become unsanitary it would be a simple matter to detach the same and fasten a new one in its place to the closure disk 4.

If it should become necessary to more assuredly fix the latch 5 in its proper operative position, the ends 6 of the band 1 may be bent over the sides of the latch 5 as shown by dotted lines in Fig. 5 thus preventing the latch from accidental displacement and permitting the bottle to be conveniently shipped without danger of the cap becoming loosened.

From the foregoing it will be observed that a very simple and durable bottle stopper has been provided, the details of which embody the preferred form. I desire it to be understood however, that slight changes

in the minor details of construction may be made without departing from the spirit of the invention or the scope of the claim 25 hereunto appended.

I claim:

A bottle stopper comprising a retaining band having its ends turned outwardly to lie parallel in spaced relation; a closure disk 30 hingedly connected to the band at a point diametrically opposite to said spaced ends, and a latch carried by the disk and having a slot to receive the said spaced ends when the disk is closed whereby the said ends 35 are held in contact, and the said latch maintained in operative position.

In testimony whereof I affix my signature in presence of two witnesses.

MRS. AMANDA OBERG.
